ILLUMINABLE DISPLAY STAND FOR TRANSPARENCIES OR THE LIKE

David H. Choiniere, P.O. Box 262, and Lloyd A. Pelky,
P.O. Box 334, both of Plover, Wis.

Filed Feb. 24, 1965, Ser. No. 83,963

Term of patent 14 years

(Cl. D80—11)

FIG. 1 is a front elevational view of an illuminable display stand for transparencies or the like embodying our new design;

FIG. 2 is an elevational view taken from one side thereof, the opposite side being essentially the same as that shown;

FIG. 3 is a fragmentary rear elevational view of top portion thereof; and

FIG. 4 is a top plan view thereof.

The broken line representation of transparencies in FIGS. 1 and 3 are for purposes of illustration only.

We claim:

The ornamental design for an illuminable display stand for transparencies or the like, as shown and described.
